(57) **CLAIM**

The ornamental design for a cortical tibial suspension fixation device as shown and described.

DESCRIPTION

FIG. 1 is a top perspective view of a cortical tibial suspension fixation device;

FIG. 2 is a bottom perspective view thereof;

FIG. 3 is a front elevation view thereof, the rear elevation view being identical thereto;

FIG. 4 is a left side elevation view thereof, the right side elevation view being identical thereto;

FIG. 5 is a top plan view thereof; and,

FIG. 6 is a bottom plan view thereof.

The broken lines illustrate portions of the cortical tibial suspension fixation device that form no part of the claimed design.

1 Claim, 6 Drawing Sheets
